UNITED STATES PATENT OFFICE.

FRANK G. McPHERSON, OF BEAVER FALLS, PENNSYLVANIA.

PLAYING-CARDS.

977,117.

Specification of Letters Patent. Patented Nov. 29, 1910.

Application filed March 9, 1910. Serial No. 548,247.

To all whom it may concern:

Be it known that I, FRANK G. McPHERSON, a citizen of the United States, residing at Beaver Falls, in the county of Beaver 5 and State of Pennsylvania, have invented new and useful Playing-Cards, of which the following is a specification.

My present invention relates to improvements in games played with cards, and more 10 particularly to those games which embody the principle of playing appropriately designated cards in sequence.

The primary characteristic of my improved game is the application to the cards 15 of letters or other characters which are arranged in groups and which, when assembled in a prescribed sequential relation, automatically announce the termination of the game and also inform the opposed players 20 of their respective standing as to the result of the game.

In the preferred embodiment of my invention, the cards are inscribed with letters 25 at their opposite ends, and these letters are so arranged that when a single card from each group of cards is played to the table in sequential order, the player winning the game will be enabled to read the words "I win," while the opposed player will have 30 facing him the words "You lose." For this reason, I have called the game "I win, you lose."

In the accompanying drawings, Figure 1 is a plan view showing the winning combination of cards. Fig. 2 is a plan view of 35 a series of cards, any one of which may constitute the first card of the winning combination, and showing the said series of cards arranged in four minor series or groups. Fig. 3 is a plan view of a group of cards, 40 any one of which may form the second card of the winning combination. Figs. 4 and 5 are similar views of the remaining cards.

On referring to the accompanying drawings, it will be noticed that my game apparatus consists primarily in a series of four cards 1, 2, 3 and 4, which are provided at 45 their diagonally opposite corners with numerals 5 denoting the sequence in which the cards may be played to form the winning combination of cards and also denoting the trick-winning value of the cards. These cards are also provided at their diagonally- 50 opposite corners and immediately below the indexes 5 with characters 6 indicative of suits in the playing of the cards in tricks.

Each card is divided transversely at its center on its face by lines or similar division marks 7, and upon the face of each card at the opposite sides of said division marks are 50 printed or otherwise inscribed letters or other characters 8 and 9 which are of dissimilar nature and which, when the cards are assembled in their proper sequential relation, will spell the two sentences "I win" and 55 "You lose." In the particular arrangement of the cards illustrated in the drawings, the card numbered 1, and bearing the numeral 1 as its index, is marked at one end with the letter "I" and at the opposite end with the 60 letters "Se," the said letters being so arranged that the base or lower end of each letter is toward or adjacent the transverse division line of the card. The second card, or the card bearing the numeral 2 as its index, is inscribed with the letter "W" at 65 one side of its central division line and with the letters "Lo" at the opposite side of the same, and in like manner the card marked with the numeral 3 carries the letters "I" 70 and "U" at its opposite ends, while the card marked "4" has the letter "N" at one end and the letters "Yo" at the opposite end, it being particularly noted that on the card marked 3, the letter "U" is closer to 75 one side edge than to the other side edge, so that when the cards are finally assembled in their proper order, the said letter will appear in its proper relation to the letters 80 "Yo" so as to form the word "You." In 85 order to further facilitate the proper placing of the cards and the reading of the same in playing the game as well as to readily distinguish between the characters at the opposite ends of the cards, the letters at the 90 opposite ends are preferably printed in contrasting colors, for instance, the letters "I," "W," "I" and "N" are printed in red while the letters at the opposite ends of the cards 95 are printed in black. The game could be 100 played with the four different cards, void of suit characters, but in order to increase the chances against a player holding the combination of cards necessary to win, I prefer to provide a plurality of cards bearing each 105 designation and the group of cards having the same designation are subdivided into suits, that is to say, a plurality of cards bearing the letters "I" and "Se," for instance, 110 will be provided and each card bearing those letters will be marked with the numeral 1, but the character 6 on all the cards bearing

the numeral 1 will not be the same. In the particular illustration, the cards are sub-divided into four groups of three cards each, and the cards in the respective groups are 5 designated by the letters A, B, C and D, although the suit characters of the ordinary pack of cards may be used instead of these letters. It will thus be seen that there are twelve of each of the four individual kinds 10 of cards, and that each group of twelve cards is sub-divided into minor groups or series of three cards each. Such an arrangement will provide a pack of forty-eight cards, as is obvious, but if a large number of players 15 are to engage in the game, the pack may be increased to any desired extent. While various rules for playing the game may be formulated, I will describe the manner in which I consider the most entertainment 20 and instruction may be derived from the playing of the game.

In starting the game, the dealer is determined by lot or otherwise, according to the agreement of the players participating, and 25 nine cards are dealt to each player after the pack has been thoroughly shuffled. Should it be necessary, the discards may be shuffled and re-dealt in order to finish the game, but ordinarily the cards dealt from the pack in 30 the ordinary course will suffice for the playing of a game. The player next to the dealer leads by playing any card in his hand to the center of the table face upward and the opposing player will be required to play 35 a card from his hand upon the card so led. In playing to the trick, the following player may play any card in his hand, provided that if he has a card of the same suit he must play that card. The card of the suit 40 led having the higher trick-winning value will win the trick and the winner of the trick will then lead. In playing the tricks, card number 1 will win over card number 4 but will not win over any other card, while 45 card number 4 will win over only card number 3, 3 will win over 2 only, and 2 will take 1. The winner of the trick will, if he can, place it before him on the table so that the last card played to the trick will appear in 50 the proper place to complete or add to the combination of cards exposed before him on the table, but if the trick is incapable of use in that combination, it will be put aside as a discard. The winner of the trick will 55 then lead again and he will continue to lead as long as he wins the tricks played, the object, of course, being to either force his opponent to take the lead or to play a card which will enable the leader to complete the 60 combination of cards spread upon the table before him to win the game. Should the player leading to the table succeed in taking in tricks containing one card of each group, he may place the same upon the table in 65 front of him so as to form the words "I

win," whereupon the words "You lose" will be simultaneously formed and face the opponent, the forming of these words indicating the termination of the game and also announcing the winner and loser. For example, if the leader should play card 2 suit A, it will be necessary for his opponent to play card 3 suit A in order to win the trick. Should the opponent play that card and take the trick, he may place the trick in position No. 3 before himself. Should the opponent not hold card 3 suit A, he will play whatever card he may best spare and the leader will win the trick. Supposing the card played to the trick to be 4 D, the leader 70 will take the trick and place it before himself in position No. 4, but if that position should be already filled, the trick must, of course, be put in the discard. If the player playing to a trick on the table has no cards 75 of the suit led, he is, of course, at liberty to play any card he may please, and in that case he will, of course, try to play a card which his opponent already has exposed on the board before him and thereby prevent 80 the said player from filling out the desired succession of cards.

The game may be played by any number of persons, either individually or as partners, and the cards may be multiplied so as 90 to form a pack of any desired size in order to accommodate a large number of players. In placing the cards on the table to form the desired combination, the suits of the cards may be disregarded entirely but it is 95 necessary to arrange the cards in sequence, according to the index 5 upon each card so that when the cards have been placed side by side in their numerical order, as determined by that index, the desired combination of 100 letters will be formed. Inasmuch as the desired characters to form the winning combination are printed in red, the players participating in the game will naturally disregard the opposite ends of the cards, but as 105 the cards are disposed in groups according to the indexes in the corner of the same, the formation of the winning combination will necessarily and simultaneously form the sentence which will announce to the loser his 110 undesirable position in the game.

The cards may also be utilized for playing solitaire, as for instance, by drawing from the top of the deck, playing the first card with the red side up and playing continuously alternately from the black and red ends of the cards. In playing either color, suits will be disregarded but the cards, of course, will be placed in their proper sequence and the cards which do not fit in 115 this sequence must be discarded, the numerical order on the red side reading from left to right and on the black end reading from right to left in order that the letters 120 may appear in their proper upright posi- 125

tions. Should the red combination be first completed, the player will read the words "I win" but should the black combination be first completed he will read the words 5 "You lose."

The cards are inexpensive to produce and are attractive in appearance. The game is simple so that it may be readily understood by a novice or a child, but it also possesses 10 possibilities for considerable study and consideration so that the powers of observation and memory will be developed and trained, all of which will be readily appreciated.

Instead of the words "I win, you lose," 15 the cards may be changed to express the same meaning but in different language, thus: "We win, you lose," or "I won, you lost," etc.

Having thus described the invention, what 20 I claim as new, and desire to secure by Letters Patent, is:—

1. A game apparatus comprising a pack of cards having sequential relation and bearing characters which, when the cards are 25 assembled in their sequential relation, indicate the termination and spell the result of the game.

2. A game apparatus comprising a pack of cards, each card having dissimilar indicia at its opposite ends, and the cards having a sequential relation whereby the indicia on the assembled cards will spell words to announce to the opposed players their relative standing at the close of the game.

3. A pack of cards consisting of groups 35 having a sequential relation, the cards of each group being provided with characters on their faces which when the cards are assembled in the sequential order of the groups will spell an announcement indicating the 40 termination and also the result of the game.

4. A pack of cards comprising four cards having a sequential relation provided on their faces, at opposite sides of their transverse centers, with the characters "I" and "Se," "W" and "Lo," "I" and "U," and "N" and "Yo" respectively, whereby when 45 the cards are exposed in the order of play

they will simultaneously spell announcements reading "I win" and "You lose" facing 50 the opposed players.

5. A pack of cards composed of several groups having a sequential relation, each card being divided transversely by lines and having letters on each division, all the cards 55 of each group having the same letters but the letters on the cards of one group differing from the letters on the cards of the other groups, which letters when the cards of different groups are assembled in their 60 proper order will indicate the termination and spell the result of the game.

6. A pack of cards composed of four groups having a sequential relation, the cards in each group being sub-divided into 65 suits, each card being divided transversely by lines and having letters on each division, the letters reading in different directions, all the cards of each group having the same letters but the letters on the cards of one 70 group differing from the letters on the cards of the other groups, which letters when the cards of different groups are assembled in their proper order, will indicate the termination and spell the result of the game, 75 each card being provided at its diagonally opposite corners with numerals denoting the sequence in which the cards may be played and below the numerals with characters indicative of the suits, the numerals 80 on the cards of each group being different but the characters being the same.

7. A pack of cards composed of several groups of cards having a sequential relation, each card bearing letters which when the 85 cards are assembled in their sequential relation, spell the words "I win, you lose," or words of similar import, announcing the result of the game.

In testimony, that I claim the foregoing 90 as my own, I have hereto affixed my signature in the presence of two witnesses.

FRANK G. MCPHERSON.
